UNITED STATES PATENT OFFICE

165,135

RECEPTACLE FOR TOILET ARTICLES

Clarence C. Christensen, Muskegon, Mich., assignor, by mesne assignments, to James J. Hamm

Application August 8, 1949, Serial No. 4,362

Term of patent 3½ years

(Cl. D4—3)

To all whom it may concern:

Be it known that I, Clarence C. Christensen, a citizen of the United States, residing at Muskegon, in the county of Muskegon and State of Michigan, have invented a new, original, and ornamental Design for a Receptacle for Toilet Articles, of which the following is a specification, reference being had to the accompanying drawings, forming part thereof.

Fig. 1 is a front upper perspective view of a receptacle for toilet articles, showing my new design.

Fig. 2 is a top plan view of the same.

Fig. 3 is a front lower perspective view of the same.

I claim:

The ornamental design for a receptacle for toilet articles, substantially as shown.

CLARENCE C. CHRISTENSEN.
